ATTORNEYS

UNITED STATES PATENT OFFICE.

LULU GRIMM BLASIER, OF WILLIAMSBURG, IOWA.

DESIGN FOR A SPOON.

No. 38,624.

Specification for Design.

Patented June 18, 1907.

Application filed May 23, 1907. Serial No. 375,359. Term of patent 14 years.

To all whom it may concern:

Be it known that I, LULU GRIMM BLASIER, a citizen of the United States, and a resident of Williamsburg, in the county of Iowa and State of Iowa, have invented a new, original, and ornamental Design for a Spoon, reference being had to the accompanying drawing, in which the figure is a plan view of a spoon, showing my design.

I claim:
The ornamental design for a spoon, as shown.

LULU GRIMM BLASIER.
